UNITED STATES PATENT OFFICE

138,065

DESIGN FOR A TUBULAR MEMBER FOR METAL FURNITURE, STANCHIONS, GUARDRAILS OR THE LIKE

Albert L. Heck, Normandy, Mo., assignor to
American Fixture & Manufacturing Co., St.
Louis, Mo., a corporation of Missouri

Application February 5, 1944, Serial No. 112,460

Term of patent 14 years

(Cl. D54—7)

To all whom it may concern:

Be it known that I, Albert L. Heck, a citizen of the United States, residing at Normandy, county of St. Louis, State of Missouri, have invented a new, original, and ornamental Design for a Tubular Member for Metal Furniture, Stanchions, Guardrails, or the like, of which the following is a specification, reference being made to the accompanying drawing, forming a part thereof, in which Figure 1 is a broken rear

elevational view, Figure 2 is a fragmentary front elevational view, and Figure 3 is a fragmentary side elevational view of a tubular member for metal furniture, stanchions, guardrails, or the like, embodying my new design.

I claim:

The ornamental design for a tubular member for metal furniture, stanchions, guardrails, or the like, substantially as shown.

ALBERT L. HECK.
